(57) **CLAIM**

The ornamental design for a led grow lamp, as shown and described.

DESCRIPTION

FIG. 1 is a bottom, front perspective view of a led grow lamp showing my new design;

FIG. 2 is a front view thereof;

FIG. 3 is a rear view thereof;

FIG. 4 is a right side view thereof;

FIG. 5 is left side view thereof;

FIG. 6 is a top view thereof;

FIG. 7 is a bottom view thereof;

FIG. 8 is a front view of the led grow lamp showing with holder; and,

FIG. 9 is an extended view of the Led Grow Lamp showing with connected holders.

The broken lines in the drawings depict portions of the led grow lamp that form no part of the claimed design.

The curved broken line at the sides of the led grow lamp with holder in FIG. 8 defines the bounds of the claimed design and forms no part thereof.

1 Claim, 9 Drawing Sheets
